(57) **CLAIM**

I claim a new ornamental design for a front plate for a bicycle, as shown and described.

DESCRIPTION

FIG. 1 is a front perspective view of a bike front plate embodying the new design;

FIG. 2 is a front elevation view of the bike front plate of FIG. 1;

FIG. 3 is a side elevation view of the bike front plate of FIG. 1;

FIG. 4 is a top plan view of the bike front plate of FIG. 1; and, FIG. 5 is a bottom plan view of the bike front plate of FIG. 1. The structure illustrated in broken lines is environmental in nature and forms no part of the claimed design.
